UNITED STATES PATENT OFFICE.

HENRY D. BARAGWANATH, OF CHICAGO, ILLINOIS.

FEED-WATER HEATER AND PURIFIER.

SPECIFICATION forming part of Letters Patent No. 402,645, dated May 7, 1889.

Application filed August 28, 1888. Serial No. 283,994. (No model.)

To all whom it may concern:

Be it known that I, HENRY D. BARAGWANATH, a citizen of the United States, residing in Chicago, in the county of Cook and State 5 of Illinois, have invented certain new and useful Improvements in Feed-Water Heaters and Purifiers, of which the following is a specification.

This invention relates to improvements in 10 feed-water heaters for purifying and heating the water prior to being fed into the boiler, by removing the mud, lime, and scale forming substances usually held in solution in feed-water.

15 The prime object of this invention is to simultaneously heat and purify the water by passing it through a heating-chamber in a shallow stream, whereby the action of the heat is rendered most effectual in precipitating 20 the scale-forming substances, as well as in raising the temperature of the water.

Another object is to materially increase the 25 time which the water is subjected to the action of the heat, and thereby promote the effectiveness of the heating and purifying operation by passing the water through the heating-chamber in a shallow stream and in a zigzag path from end to end of the heating-chamber.

30 A further object is to so connect the heater with the boiler as to avoid a siphon action upon the feed-water pipe, whereby the feed to the boiler may be made by gravity without danger of feeding any sediment from the settling-chamber. I attain these objects by the 35 devices illustrated in the accompanying drawings, in which—

Figure 1 is a central vertical section through the feed-water heater and settling-chamber 40 embodying my invention; Fig. 2, a transverse vertical section thereof, showing the settling-chamber in elevation.

Similar letters of reference indicate the 45 same parts in the several figures of the drawings.

Referring by letter to the accompanying drawings, A indicates a horizontal heater or chamber having removable heads or end caps, B, bolted or otherwise secured thereto, in the 50 center of each of which is inserted a screw-plug, C, for permitting inspection of the interior of the boiler without necessitating the

removal of the heads. Within this heater is arranged a series of inclined shelves, D, extending substantially the entire length of the 55 horizontal boiler, and each shelf inclined in an opposite direction from that immediately beneath it, so that their surfaces form a zig-zag path, beginning at the top and extending over any number of intermediate shelves 60 about two-thirds the depth of the boiler, the highest end of each shelf being provided with an upturned lip or flange, E, which prevents the water which flows thereon from the next shelf above from overflowing at that end. 65 These shelves preferably rest upon ribs or lugs F, arranged along the side walls of the boiler, and extending from one side to the other of the boiler in a substantially horizontal plane, being slightly curved downwardly 70 from a true horizontal position, so as to cause the water to flow toward the center thereof, as more clearly shown in Fig. 2, the shelf being merely set upon the ledges, and readily removable therefrom when the end caps of 75 the boiler are removed.

Steam is admitted into the heater through a pipe, G, while the water enters through pipe H, both at the top of the boiler, from whence the water flows successively over the 80 inclined shelves in a zigzag path, and in a shallow stream of substantially the entire width of the shelf, until it reaches the bottom shelf, from whence it falls into the lower part of the boiler, escaping therefrom into a settling-chamber, I, arranged beneath the boiler and connected therewith by a pipe, J, the open end of which extends up into the boiler nearly to the lower shelf, thus converting the lower part of the boiler into a settling-chamber, 85 from whence the mud and other foreign substances may be blown off through the pipe K, leading from the bottom thereof near one end. The feed-water overflowing the pipe J falls into the settling-chamber I upon a hollow cone-deflector, L, which protects the upper and open end of a short vertical pipe, M, the lower end of which opens in the settling-chamber below the surface of the water 90 therein, and with which pipe, near the upper end thereof, is connected the feed-pipe N leading to the boiler. The settling from the overflow-water into this chamber sink to the bottom thereof, and are occasionally blown 95

off through the pipe O, thus relieving the chamber of the mud, sediment, and other foreign substances which have been released from the feed-water during its passage through the heater, but not retained in the heater, thus acting in the nature of a safeguard and check on the heater, so as to insure the purity of the feed-water before its delivery to the boiler. The main portion of the impurities in the water, however, and especially the scale-forming substances, which are the most injurious to a boiler, are precipitated and retained upon the shelves D during the passage of the water across the same, the broad and shallow stream rendering the precipitation effective in a maximum degree, and hence it is necessary at intervals to take out the shelves and remove the scales therefrom.

This heater is designed to be set at a sufficient height relative to the boiler to insure the feeding of the water thereto by gravity, the pipe N leading to the boiler being at a height of eighteen inches or two feet above the highest level of the water in the boiler, and to prevent the siphon action of the feed-water whenever the continuous feed is stopped I have provided the pipe M with the protected open end above its connection with the boiler feed-pipe, so that whenever the water in the settling-chamber falls below the level of the boiler feed-pipe N the feed of the water will cease, and the sediment from the bottom of the settling-chamber will not be drawn up and fed into the boiler by a siphon action, as would otherwise occur.

In conclusion, I may state that the shelves,

instead of being curved and independently removable, as shown, may be perfectly flat with upturned side edges, and all formed into one frame, so as to be removed simultaneously from the heater, the essential feature being to provide the heater with reversely-inclined shelves, so as to cause the feed-water to traverse a zigzag path in passing through the heater.

Having described my invention, what I claim, and desire to secure by Letters Patent, is—

1. The combination, with the feed-water heater, of a settling-chamber, a vertical pipe therein opening at both ends above and below the surface of the water, respectively, a hollow cone protecting the upper end thereof, and a feed-pipe leading to the boiler and connecting with said pipe below the upper protected end thereof, substantially as described.

2. The combination, with a feed-water heater, of a series of reversely-inclined shelves located in the heating-chamber thereof, a settling-chamber and pipe connecting said chamber and heater and opening in the latter above the bottom thereof, a vertical pipe within said chamber open at both ends, the lower end only being submerged, a cone protecting the upper open end thereof, and a feed-pipe to the boiler connecting with said pipe below the upper protected end thereof, substantially as described.

HENRY D. BARAGWANATH.
